UNITED STATES PATENT OFFICE.

BARTLEY E. BROADWELL, OF NIAGARA FALLS, NEW YORK.

FURNACE CONSTRUCTION.

1,351,281.

Specification of Letters Patent. Patented Aug. 31, 1920.

Application filed March 19, 1919. Serial No. 283,470.

To all whom it may concern:

Be it known that I, BARTLEY E. BROADWELL, a citizen of the United States, residing at Niagara Falls, in the county of Niagara and State of New York, have invented certain new and useful Improvements in Furnace Construction; and I do hereby declare the following to be a full, clear, and exact description of the same, 10 reference being had to the accompanying drawings, forming part of this specification.

This invention relates to what is known as ring type furnaces, which consists of a series of baking chambers so arranged that 15 in the heating of one of the chambers the hot waste gases will warm up the chambers in advance and at the same time the chambers on the other side of the chamber being heated will warm up, in their cooling, the 20 air which is to be burned in the chamber now under fire, thus permitting a constant or ring action of the furnace as a whole, all the chambers of the furnace being successively heated in turn.

25 The objects of the present invention are to improve the method of circulating the gases in such a furnace and to provide means whereby complete observation of each individual chamber is permitted in order to 30 closely regulate the heat therein and the time of baking. The method of circulating the gases is distinct from previous practice in furnaces of this type in that, instead of passing such gases in a generally horizontal 35 direction, as is common in ring furnaces of known types, I cause the major portion of the gases to pass through the flues of an oven being warmed up or preheated, first directly upward the entire height of the 40 oven, then downwardly beneath a baffle in the flue on either side of the oven, then upwardly through a central chamber and over a second baffle, and thence downwardly again through the front chamber to ports 45 leading to the next vertical duct or flue, which is located directly in front of the oven being preheated, thus giving the major part of the gases (about three-fourths in volume) a generally vertical travel up and 50 down about the walls of the oven. The path of the air around an oven being cooled is the same as that through a similar oven being heated, so the saving of fuel in my improved furnace is very material.

55 A complete survey of the interior of the furnace flues is permitted by arranging an

observation hole immediately over the point at which the fuel gas meets the stream of strongly heated air, a second hole directly in the center, both laterally and longitudinally of the middle chamber in which the flame ascends, and a third observation hole directly against the front wall of the flue directly over the last port of emission from the gas flame.

60 Other objects of this invention are to improve generally furnaces of this type and to alter the construction of details of the same in order to increase the ease of operation thereof.

65 In the drawings,—

Figure 1 is a plan view of a portion of a ring type furnace embodying the features of my invention.

70 Fig. 2 is a sectional elevation on the line 2—2 of Fig. 1, showing a vertical section through one of the pits in which the articles to be heated or baked are placed.

75 Fig. 3 is a sectional elevation on the line 3—3 of Fig. 1, showing a vertical section through the center of one of the gas flues.

80 Fig. 4 is a horizontal sectional view on line 4—4 of Fig. 3, showing particularly the passageways under the gas flues and pits.

85 Fig. 5 is a horizontal sectional view on line 5—5 of Fig. 3, showing particularly the chambers into which the gas flues are divided.

90 Fig. 6 is a vertical section taken on line 6—6 of Fig. 1, showing the vertical ducts in the head walls which separate the several sets of gas flues and pits, and also the cross section of one of the flues.

95 Fig. 7 is a section on line 7—7 of Fig. 1, showing the ducts in the head walls.

100 Referring now to Fig. 1 of the drawings, wherein is shown a typical section of a ring type furnace embodying my invention, 7 represents the central fuel gas main which extends the entire length of the furnace, 100 being provided with a number of ports 8, 8, from any one of which fuel gas may be led into the inlet ports 9, 9, of the gas flues of the respective set corresponding to such port 8 by means of a removable pipe 10 having 105 connections 11 with each of the gas inlet ports 9 of such a set of parallel flues, such connections 11 each being provided with a manually controlled valve 12 for regulating the supply of gas into the individual flues. 110 The pipe 10 is intended for use with each of the different sets of flues and is supported

as best shown in Fig. 6 by means of the yoke 13 and chains 14 from a trackway (not shown) extending around the furnace above the pits. The ports 8 when not in use for supplying fuel gas to the flues are closed by covers 15, and the inlet ports of all of the remaining gas flues 9 are likewise closed by covers 67 when firing of that set is completed.

10 Arranged transversely on either side of the gas main 7 and at right angles thereto are head walls 16 extending from the gas main to the waste main 17, these heads serving to separate the pits and flues into sets, 15 each set consisting of five pits and six flues alternately arranged parallel to the gas and waste mains. The head walls 16 are provided with a vertical duct 18 for each pit, each duct ending in a chimney 19 extending 20 above the level of the top of the pit 20, and such ducts are connected at their upper section about on the same level as the fuel gas main, that is, just below the top of the pits 20 by a transverse horizontal passageway 21 opening into each duct and extending on 25 either side of the end ducts as far as the side gas flues 23 and 24. The upper wall of the head is perforated centrally of each of gas flues 22 forming a vent 25 in line 30 with an orifice 26 in the end wall of the gas flue, thus permitting gases to pass from the vertical ducts 18 to the gas flue 22. Each gas flue is divided into three approximately 35 equal chambers 27 by means of a baffle 28 extending a little more than one-half of the way down from the roof or crown 29 and a similar baffle 30 extending an equal distance upwardly from the floor 31 so as to be somewhat higher than the bottom of the baffle 28, this construction being best shown in 40 Fig. 3.

Observation holes 32, 33 and 34 are provided in the roof 29 of each gas flue in the longitudinal center line thereof, the forward 45 observation hole 34 being located at the extreme front, closely adjacent the front wall 35 of the flue, which wall does not join the head 16, but is spaced therefrom so as to provide a dead air space 37 which serves as an expansion joint and prevents displacement of the head by the expansion of the gas flue when heated. A similar expansion joint 38 is provided between the rear wall 39 and the adjacent head wall 16. The rear 50 observation hole 32 is arranged as close as possible to the gas inlet 9, in order to see more clearly the combustion flame, and the middle observation hole 33 is arranged centrally of the middle chamber 27, making the distance 55 between the observation holes 32 and 33 the same as the space between the observation hole 32 of one gas flue and the observation hole 34 of the next gas flue.

Under each pit 20 are located a pair of 60 longitudinal channels 40 separated by a par-

titon 41 and extending the entire length of the pit and communicating at their forward end with the adjacent vertical duct 18 in the head wall 16. Each of these channels 40 communicates with the flue on the nearest 65 side by means of a pair of ports 42 at the extreme rear of the pit, and by means of three larger ports 43 at the forward end of the pit, each of these ports 42 and 43 extending completely under the adjacent gas 70 flue 22 and communicating with the chamber 27 immediately above the same, that is, each of the ports 42 opens vertically upward into the rear chamber 27 immediately below the gas inlet 9 and each of the ports 43 communicates with the forward chamber 27, the front port 43 being directly under observation hole 34.

The pits, it will be noted, are open at the top as the term denotes, and are closed on 85 the side by the walls 50 of the gas flues which, as will be seen from Fig. 6, do not rise flush with their bases 51, but form a ledge 52, which, with the partition 41, forms a support or piers for the fire bricks 53 90 which bridge the parallel longitudinal channels 40 and form the floor 54 of the pit. The ends of the pit are closed by the head walls 16, which are at this place practically hollow chimney structures since the ducts 18 95 are nearly as wide as the pits. These walls 16, however, extend as solid masonry from the wall of one flue to the wall of the next, except for the upper portion where they are pierced by the transverse passage 21 and 100 its communicating short vents 25.

The tops of the gas flues are capped by blocks 56 extending from one wall 50 to the other, and forming the roof or crown 29 of the gas flue, the upper surface of which is 105 about a foot or more below the ground level in my preferred construction, the observation holes, gas inlets, and chimneys all being raised to such level by shafts or casings as shown, so that, the entire roof structure 110 may be covered with sand or other heat insulator, when it is so desired.

A slot 57 is provided between the head wall 16 and the rear wall 39 in which slot is placed a damper 58 to close the exit 115 formed by the vent 25 and orifice 26. This damper can be handled directly from the surface by moving back the tile 59 which rests on the top of the head wall 16 and acts as a seal over the slot 57 whether the damper 120 58 is in the slot or not. The damper may be of refractory material, sheet metal, paper or fabric, provided that such paper or fabric possesses a compactness sufficient to yield a low enough porosity to prevent the leakage of any appreciable amount of gas or air through it. In case paper is used, it is tacked on a frame and dropped into the slot, and when it is desired to open another pit, and therefore move the damper farther 125 130

along the furnace, it is simply necessary to knock a hole in the paper of the one to be eliminated, and the direction of the flow of hot gases is changed and will in a short duration of time burn out the remainder of the paper.

The waste gases, when deprived of the greater part of their heat by passing through five or more sets of units (each set consisting of eleven parallel units, as heretofore described) is passed out the chimneys 19 to waste main 17, by means of a removable pipe 60 swung from an overhead track (not shown) by means of chains 61. A main connection 62 fits over the port 63 of the main 17 and other smaller connections 64, each provided with a manually controlled damper 65, fits over the chimneys 19, the covers 66 of which are removed for such purpose.

It has been found unnecessary to connect all the chimneys with the waste gas main and I find it sufficient to only so connect each alternate chimney of the set.

I will now describe the operation of my improved furnace in its preferred construction, consisting of twenty-eight sets of eleven units each, arranged compactly with a battery of fourteen such sets on either side of the centrally disposed fuel gas main, the two waste gas mains lying on the outside of the batteries and being connected in the usual way to a stack or exhaust not shown, but of the usual construction. The end units of each battery are connected to the adjacent unit of the battery opposite by flues and passageways as nearly like the connections between adjacent units as possible so that, numbering the sets in order in the sequence denoting the passage of gas from a lower to higher numbered set, the hot or cold gases would pass from No. 28 to No. 1 in just the same manner (except for distance) as in passing from No. 1 to No. 2.

Considering now that set No. 12 is under fire, and that Nos. 13 to 17 are being heated by the burned gases, Nos. 7 to 11 are being cooled by the air being drawn into No. 12, and Nos. 4 to 6 are available for unloading and loading. The operation is as follows: Covers 66 of chimneys 19 of the head in advance of the set (No. 6) of pits being emptied is removed and air is either drawn or forced through the ducts 18 and passes through vent 25 and orifice 26 through the next gas flue 22 (set No. 7) passing partly downward through the ports 42 into the longitudinal channels 40 and partly through the three chambers 27 and thence into the channels 40 through the forward ports 43 and thence upwardly through the next ducts 18 (No. 8), and so on, through the successive units to be cooled, finally arriving at the head wall 16 at the rear of the set 65 being fired (No. 12), and the now heated

air passes up ducts 18 and out orifice 26 in close contact with the gas being admitted through inlet port 9 of the flue being heated (set No. 12) forming a long flame which extends downwardly through rear chamber 70 27, thence upwardly through middle chamber 27 and finally downwardly again in the forward chamber 27, thence passing through the horizontal ports 42 to the duct 18 in the next head wall 16, separating the set of pits and flues under fire (No. 12) from the next successive set of pits and flues (No. 13), serving to heat the same preparatory to their being fired. The course of the heated gases is similar to that heretofore described in connection with the cold air, the single difference being that the waste gases when deprived of their heat at the set (No. 17) of flues next behind the pits being loaded (No. 18) are allowed to pass to the waste gas main 17 by the means previously described, the dampers 58 having been placed in the slots 57 of the head wall between sets Nos. 17 and 18 to isolate sets 18 to 20 for loading and unloading, two opposite sets being under fire at all times. In the present case, set No. 26 is also under fire so that Nos. 21 to 26 are cooling, and the dampers in the head wall between Nos. 3 and 4 are in place and the waste gas pipe 60 95 is connecting the chimneys of that wall with the main 17.

The tops of the pits are closed in any desired manner, for example, when the furnace is used to bake carbon electrodes, the 100 green rods are piled in the pits in the usual manner, and the entire charge is covered with a considerable thickness of carbon dust or other heat non-conductor which serves the dual purpose of retaining the heat and preventing oxidation of the electrodes by contact with air.

While I have described my invention in connection with a rectangularly arranged carbon baking furnace I wish it distinctly understood that the terms herein used are intended to cover annular furnaces, and kilns for other material than carbon.

Claims for the head arrangement illustrated herein are included in application No. 283,469, filed concurrently herewith by Albert G. Smith and myself and bearing similar title.

What is claimed is:

1. In a ring furnace, the combination 120 with a plurality of interconnected gas flues arranged longitudinally of said furnace, of pits arranged parallel to said flues and in proximity thereto and having a passageway extending beneath same throughout 125 their length and connecting with one of said flues, and a vertical baffle in one or more of the flues.

2. In a ring furnace, the combination 130 with a plurality of interconnected gas flues

arranged longitudinally of said furnace, of pits arranged parallel to said flues and in proximity thereto and having a passageway extending beneath same throughout their length and connecting with one of said flues, and vertical baffles in one or more of the flues.

3. In a ring furnace, the combination with a plurality of interconnected gas flues arranged longitudinally of said furnace, of pits arranged parallel to said flues and in proximity thereto and having a passageway extending beneath same throughout their length and connecting with one of said flues, and vertical baffles in each of the flues.

4. In a ring furnace, the combination with a plurality of gas flues arranged longitudinally of said furnace, of pits arranged parallel to said flues and in proximity thereto, a hollow head wall at the ends of each flue, and passageways connecting the hollows of adjacent head walls, passing part of the gases through the flues and the remainder of said gases under the floor of said pits, lengthwise thereof.

5. In a ring furnace, a plurality of hollow head walls, pits between said walls, and gas flues between said walls parallel to said pits and having a passageway therein causing the gases to travel in a path the vertical component of which is considerably greater than its horizontal component.

6. In a ring furnace, a plurality of parallel series of gas flues, each series consisting of a plurality of interconnected flues each extending longitudinally of the furnace,

pits arranged between the series of flues and in proximity thereto, and passageways for leading gases from flue to flue in two paths.

7. In a ring furnace, a plurality of parallel series of gas flues, each series consisting of a plurality of interconnected flues each extending longitudinally of the furnace, pits arranged between the series of flues and in proximity thereto, and a passageway through each flue connecting the adjacent flues of the series, guiding the gases up and down through the entire length of the flue.

8. In a ring furnace, a plurality of parallel series of gas flues, each series consisting of a plurality of interconnected flues each extending longitudinally of the furnace, pits arranged between the series of flues and in proximity thereto, and passageways under each pit connecting with the flues on either side of the pit.

9. In a ring furnace, a plurality of parallel series of pits, each series consisting of a plurality of pits each extending longitudinally of the furnace, and gas passageways extending under and on either side of each pit.

10. In a ring furnace, a plurality of parallel series of pits, each series consisting of a plurality of pits each extending longitudinally of the furnace, gas passageways extending under and on either side of each pit, and vertical gas passageways at either end of each pit.

BARTLEY E. BROADWELL.
